DESIGN FOR A HIGHWAY TRAFFIC SIGNAL

Robert O. Ferguson, Bristol, Tenn., assignor of
one-half to Bristol Steel & Iron Works, Inc.,
Bristol, Va., a corporation of Virginia

Application March 4, 1948, Serial No. 144,900

Term of patent 14 years

(Cl. D72—1)

To all whom it may concern:

Be it known that I, Robert O. Ferguson, a citizen of the United States, and a resident of Bristol, in the county of Sullivan and State of Tennessee, have invented a new, original, and ornamental Design for Highway Traffic Signal, of which the following is a specification, reference being had to the accompanying drawing, forming part thereof.

Fig. 1 is a front perspective view of a highway traffic signal, showing my new design; and

Fig. 2 is a rear perspective view thereof.

I claim:

The ornamental design for a highway traffic signal, as shown.

ROBERT O. FERGUSON.
